UNITED STATES PATENT OFFICE.

JAMES H. DEAN, OF LUDINGTON, MICHIGAN, ASSIGNOR TO NORTHWESTERN EXPANDED METAL COMPANY, OF CHICAGO, ILLINOIS, A CORPORATION OF ILLINOIS.

SHEET-METAL CORNER BEAD.

Application filed December 2, 1925. Serial No. 72,752.

This invention relates to corner beads such as are used in preparing walls for plastering to protect the corners and angles of the walls, and aims to provide a construction which will support the bead in a strong, rigid manner.

An object of the invention is to provide a sheet metal corner bead having a plurality of longitudinally extending corrugations forming V-shaped ribs adapted to engage the wall of the building to space the expanded panels from the wall so that the plaster may be forced through the mesh and keyed to the same.

15 In the accompanying drawings forming part of this specification:

Figure 1 is a plan view of a section of a slitted sheet of metal from which the corner bead is formed.

20 Figure 2 is a side elevation of a finished corner bead; and

Figure 3 is a horizontal sectional view showing a corner bead mounted upon the corner of a wall.

25 The corner bead featured in the invention is preferably constructed from a sheet metal blank 4 having unslotted portions 5, 6 and 7 extending longitudinally thereof, and also having groups of slits 8 cut in the metal blank between the unslotted portions 5, 6 and 7 to form meshes 9 when the strip is expanded to its finished form, shown in Figure 2.

35 The means for spacing the meshed portions of the corner bead from the faces 12 and 13 of the wall corner when mounted thereon, is shown in Figure 3. Such means preferably consists of ribs 14 formed by inwardly bending the unslotted portions of the blank as shown. The central unslotted portion 7 is preferably formed into a bead 15, spaced from the meshed portions of the corner bead by means of a neck 16, by rolling or bending the metal as shown. The unslotted portions 15 on either side of the blank are preferably provided with spaced holes

17 through which nails 18 may be inserted for the purpose of securing the corner bead to the wall as shown in Figure 3.

While I have herein shown and described an embodiment of my invention, it is to be understood that I do not desire to be limited to the specific structures shown and described, since many modifications may be made in my invention without departing from the spirit and scope of the appended claims.

I claim as my invention:

1. A corner plaster-terminal comprising a sheet metal plate of angular form having an outwardly extending bead at its angle and an inwardly projecting rib intermediate the corner bead and each edge of the sheet, and longitudinally extending expanded metal areas providing plaster holding meshes formed in the sheet metal plate between the corner bead and each inwardly projecting rib.

2. A corner plaster-terminal comprising a sheet metal plate of angular form having an outwardly extending bead at its angle and an inwardly projecting rib intermediate the corner bead and each edge of the sheet, and longitudinally extending expanded metal areas between the corner bead and each rib and similar areas between each rib and the edge of the sheet, said expanded metal areas providing plaster holding meshes.

3. A corner plaster-terminal comprising a sheet metal plate of angular form having an outwardly extending bead at its angle and an inwardly projecting V-shaped rib intermediate the corner bead and each edge of the sheet and longitudinally extending expanded metal areas providing plaster holding meshes formed in the sheet metal plate between the corner bead and each inwardly projecting rib.

In witness whereof, I have hereunto set my hand this 27th day of October, 1925.

JAMES H. DEAN.
